US00D859893S

(12) **United States Design Patent** (10) Patent No.: **US D859,893 S**
(45) Date of Patent: **** Sep. 17, 2019**

(54) **WIRE SHELVING**

(71) Applicant: **Edsal Manufacturing Company, Inc.**,
Chicago, IL (US)

(72) Inventors: **Scott Fitzgerald**, Lowell, IN (US);
David J. Wojtowicz, Orland Park, IL (US); **Thomas St. Germain**, Bridgeview, IL (US); **Mitchell Liss**, Northbrook, IL (US); **Al Dunaj**, Chicago, IL (US)

(73) Assignee: **Edsal Manufacturing Company, Inc.**, Chicago, IL (US)

(**) Term: **15 Years**

(21) Appl. No.: **29/613,802**

(22) Filed: **Aug. 14, 2017**

Related U.S. Application Data

(60) Division of application No. 29/542,570, filed on Oct. 15, 2015, now Pat. No. Des. 798,090, which is a division of application No. 29/464,476, filed on Aug. 16, 2013, now Pat. No. Des. 742,150, which is a continuation-in-part of application No. 29/461,096, filed on Jul. 18, 2013, now Pat. No. Des. 742,141, which is a division of application No. 29/365,084, filed on Jul. 2, 2010, now Pat. No. Des. 686,430.

CLAIM

The ornamental design for wire shelving, as shown and described.

DESCRIPTION

FIG. 1 is an isometric view of one embodiment of the invention;

FIG. 2 is another isometric view of the embodiment of FIG. 1;

FIG. 3 is an elevational side view of the embodiment of FIGS. 1 and 2;

FIG. 4 is an elevational end view of the embodiment of FIGS. 1 and 2;

FIG. 5 is a top view of the embodiment of FIGS. 1 and 2; FIG. 6 is an isometric view of another embodiment of the invention;

FIG. 7 is another isometric view of the embodiment of FIG. 6;

FIG. 8 is an elevational front view of the embodiment of FIGS. 6 and 7; and,

FIG. 9 is an elevational side view of the embodiment of FIGS. 6 and 7.

The dotted break lines illustrated in FIGS. 1-9 are not part of the claimed design and represent that no particular length is claimed.

1 Claim, 7 Drawing Sheets
